INVENTOR
Thomas Lund

UNITED STATES PATENT OFFICE.

THOMAS LUND, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BEADING-TOOL.

1,267,429.

Specification of Letters Patent.

Patented May 28, 1918.

Application filed September 27, 1915. Serial No. 52,859.

To all whom it may concern:

Be it known that I, THOMAS LUND, a citizen of the United States, residing at Beverly, in the county of Essex and State of Massachusetts, have invented certain Improvements in Beading-Tools, of which the following description, in connection with the accompanying drawings, is a specification, like reference characters on the drawings indicating like parts in the several figures.

This invention relates to rotary burnishing tools and in particular to rotary tools used in burnishing heels of shoes. It is customary in the manufacture of shoes such, for example, as children's shoes known to the trade as cacks to perform three burnishing operations upon the heels. The entire outside periphery of the heel is burnished, a bead is made around the outside peripheral edge and a bead is made across the breast. It is necessary to have a comparatively small beading wheel for the last operation owing to the sharp indentation at one end of the breast in this type of shoe. Heretofore it has been the practice to use three separate tools for these three operations. It is the object of my invention to provide a tool which shall be simple and convenient in operation, cheap to manufacture and by means of which a plurality of operations such as the operations above mentioned can be performed.

A feature of my invention comprises a series of relatively adjustable burnishing tools, each except one serving as a gage when the next tool of the series is in use.

Another feature of my invention comprises a series of burnishing tools, each of which in the illustrated construction is mounted on an adjacent member of the series, and serves as a tread rest when an adjacent member of the series is being used.

These and other features of the invention comprising various combinations and arrangements of parts will be best understood and appreciated from the following description of a preferred embodiment thereof selected for purposes of illustration and shown in the accompanying drawings in which,—

Figure 1 is a side elevation partially in section;

Fig. 2 is an end elevation, and

Fig. 3 is an enlarged detail of the adjusting means.

A shaft 10 is mounted in any suitable way for rotation. It has mounted at its extremity a cylindrical head 11. Slidably mounted upon the outside of the head 11 is a head 12 outside of which is similarly mounted a head 13. These three heads have the burnishing or beading elements 14, 15 and 16 respectively upon their outside edges. The surface 14 has an element 14^a adapted to run in the rand crease of a shoe.

The three heads are relatively adjustable in position, the manner of this adjustment being shown in Fig. 3. A smooth channel 17 is formed in the inside edge of the head 13 and its outside end is covered by a plate 18. The channel contains a screw 19 which can be adjusted through a small aperture in the plate 18. The screw, which turns freely in the channel 17, engages a thread 20 on the head 12 so that by turning the screw the heads 12 and 13 can be relatively adjusted parallel to their axis. A similar adjusting structure is used between the heads 11 and 12 and is shown in cross section in Fig. 1.

The outside periphery of the heel is burnished by the surface 14 as shown in Fig. 1 and at 23 in Fig. 2, the element 14^a running in the rand crease, as a guide. The beading element 15 is used to form a bead around the external periphery of the heel as is shown at 22 in Fig. 2. The front flat surface of the head 13 is used as a tread rest or gage in forming this bead. The adjustment described will make it possible to form this bead of any desired width. The small head 11 having the bead element 16 is used as shown at 21 in Fig. 2 to bead the breast of the heel, the beader 16 being of sharp curvature in order to be able to work in the indentation 24 in the breast of the heel. The front flat surface of the head 12 serves as a tread rest or gage in forming this bead. The adjustment between the heads 11 and 12 will make it possible to make this bead of any desired width. It will thus be seen that I have provided a burnishing tool which shall be compact, convenient and cheap. It will be clear that the operator can perform all three operations upon the heel without changing his position

upon the floor and without changing the position of the shoe in his hand.

Having described my invention what I claim as new and desire to secure by United States Letters Patent is:

5. 1. A burnishing instrumentality comprising a series of relatively adjustable burnishing tools each, except the last of the series, serving as a gage when the next of the series is being used.
10. 2. A burnishing instrumentality comprising a series of nested relatively adjustable burnishing tools, each of the larger tools serving as a tread rest when the next adjacent tool is being used.
15. 3. A burnishing instrumentality comprising a series of co-axial relatively adjustable burnishing tools, said tools diminishing in diameter from one end of the series to the other and each of the larger tools serving as a tread rest when the next smaller tool is being used.

4. A burnishing instrumentality comprising an edge burnishing tool having a rand engaging element, and a series of beading tools relatively adjustable to one another and to said first mentioned tool, each of said tools except the last of the series and including the first mentioned tool, serving as a tread rest when the next tool in the series is being used.

5. A burnishing instrumentality comprising a series of relatively adjustable burnishing tools, each mounted upon an adjacent one of the series, and each, except the last of the series, serving as a tread rest when an adjacent one of the series is in use.

6. A burnishing instrumentality comprising a plurality of relatively adjustable burnishing tools, one of which serves as a tread rest when another of the number is in use.

In testimony whereof I have signed my name to this specification.

THOMAS LUND.
